UNITED STATES PATENT OFFICE.

CHARLES M. ZARTMAN, OF MONTROSE, COLORADO, ASSIGNOR OF ONE-THIRD TO JAMES W. CALLOWAY AND ONE-THIRD TO ANTHONY HOBAN, BOTH OF MONTROSE, COLORADO.

WIRE-STRETCHER.

1,311,787.

Specification of Letters Patent.

Patented July 29, 1919.

Application filed July 29, 1916. Serial No. 112,157.

To all whom it may concern:

Be it known that I, CHARLES M. ZARTMAN, citizen of the United States, residing at the city and county of Montrose and State of Colorado, have invented certain new and useful Improvements in Wire-Stretchers; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in wire stretchers, my object being to provide a simple and efficient device which will overcome a number of the difficulties experienced in handling wire stretchers heretofore in vogue.

In my improvement I employ a bar which is equipped with means, preferably a chain, intermediate its extremities, adapted to pass around a post, whereby the bar is mounted upon the post and extends therefrom in both directions. Upon a holder carried near one end of this bar is fulcrumed a lever with which is connected pawls adapted to engage ratchet teeth on the bar. One end of the bar is also provided with a jointed device equipped with means for clamping the wire to be stretched. The opposite extremity of the bar is provided with a guide, through which the wire passes during the stretching operation. This last named extremity of the bar is also equipped with means for clamping the wire to the bar whenever it is desired to do so. The bar is further equipped between its extremities with a guide for the wire, whereby the latter is held in alinement with the bar during the wire stretching operation. This guide is a very important feature since it keeps the wire during the stretching operation in alinement with the bar and also directly above the same, thus rendering it impossible for the wire to get out of alinement with the edge of the bar. In wire stretchers which are not equipped with a guide of this character, the wire during the stretching operation is liable to bend the bar, the wire acting as a bow string. By virtue of my improved guide the bar may be made com-

paratively small and light in weight and still efficiently perform the wire stretching function. Were it not for this guide, it would be necessary to make the bar abnormally heavy, in order to prevent the wire from bending the bar like a bow. It will readily be understood that it is exceedingly important that the bar should be as light as possible, not only from the standpoint of cheapness of construction, but also by reason of the fact that a bar of light weight is much more easily handled during the wire stretching operation than a heavy bar. It is also much easier to carry about a light bar than one of the weight which would be required in the absence of my improved guide, located intermediate the extremities of the bar.

Having briefly outlined my improved construction I shall proceed to describe the same in detail, reference being made to the accompanying drawing, in which is illustrated an embodiment thereof. In this drawing,

Figure 1 is a side elevation of my improved wire stretcher, showing the same in use.

Fig. 2 is a fragmentary view of the same, showing the parts on a somewhat larger scale. In this view the post and the means connected with the bar for attaching the latter to the post are omitted.

Fig. 3 is a section taken on the line 3—3, Fig. 2, looking toward the right.

Fig. 4 is a detail elevation, showing one extremity of the bar with the clamping device in engagement with the wire.

Fig. 5 is a section taken on the line 5—5, Fig. 4, looking toward the left.

Fig. 6 is a view looking in the direction of arrow 6, Fig. 2.

The same reference characters indicate the same parts in all the views. Let the numeral 5 designate a bar equipped intermediate its extremities with a chain 6, one extremity of which is fixedly connected with the bar, as shown at 7. The chain is adapted to be passed around a post 9, after which one link thereof is connected with a hook or projection 8 formed on the bar and extending downwardly therefrom, thus securing the bar intermediate its extremities upon the post. In this event the bar extends both forwardly and rearwardly from the post.

The forward portion of the bar is toothed on its upper and lower edges to coöperate with pawls 10 and 12, which are pivotally mounted as shown at 13 and 14 on a lever 15; the pawl 10 is located above the bar and coöperates with the teeth of its upper edge, while the pawl 12 is located below the bar and coöperates with the teeth of its lower edge. The lever 15 is fulcrumed on a member 16, which is adapted to slide freely on the bar during the wire stretching operation. Pivotally connected with the slideable member 16 at the fulcrum 17 of the lever is a bifurcated part 18, terminating in an eye 19, which interlocks with a similar eye 20, forming a part of a hood 21 swiveled in a part 22 to form a universal joint. This part 22 is equipped with a flange 23 and an upwardly projecting part 24. When the device is in use, the wire 25 to be stretched rests upon the flange 23, and an eccentric cam 26, which is pivotally mounted on the part 24, coöperates with the flanges 23 to hold the wire securely in place during the wire stretching operation.

The rear extremity of the bar is provided with an upwardly projecting guide 36, which forms a loop through which the wire to be stretched passes. In the upper portion of this loop is pivotally mounted an anti-frictional roller 27, below which the wire passes. Pivotally connected with the rear end of the bar below the guide 26, is an angle member 28 carrying an eccentric cam 29. After the wire is stretched to the limit permitted by the length of the notched forward portion of the bar, if it is desired to further stretch the wire, the angle member 28 and the cam 29 will be thrown to the dotted line position in Fig. 1, whereby the wire will be securely clamped to the rear end of the bar. After this is done, the cam 26 is released from the wire and the slideable member 16, together with the lever 15 and the pawls 10 and 12, will be moved rearwardly and the cam 26 applied to the wire in a position considerably in the rear of its original position. As soon as this is done the cam 29 will be released from the wire and the angle member 28 will be allowed to drop down to the full line position in Fig. 1, whereby it will be disengaged from the wire. The wire stretching operation may then be continued in the same manner as before.

Intermediate the extremities of the bar 5 is mounted a guide 30, whose upper portion is forked, as shown in 31, the upper portions of the arms of the fork being sufficiently spaced, as shown in 32, to allow the wire 60 with the barbs thereon to pass freely between the arms of the fork. These arms, however, gradually approach each other at their lower extremities, the latter being arranged to hold the wire in place preparatory to the securing of the wire by the cam 26. In

other words, the operator will stretch the wire as tightly as he can by hand and then drop it into place between the arms 32 and allow it to move downwardly into position between the lower extremities of the arms, 70 in which event the barb will retain the wire in the position of hand adjustment, since the lower extremities of the arms of the fork are so close together that the barb cannot pass therethrough. However, as soon as the 75 wire stretching operation begins the wire will be automatically raised from the lower position into the wider space above between the arms of the fork, and pass freely therethrough. This guide 30 also performs another important function, since being located on the bar between the extremities thereof, it maintains the wire in alinement with its edge, and thus prevents the wire from bending the bar in the same manner as a string 85 or cord bends a bow. By virtue of this construction, I am enabled to make the bar much lighter in weight than I could otherwise do.

From the foregoing description, the use 90 of my improved wire stretcher will be readily understood. In the first instance, the chain 6 is passed around the post 9, beginning on the side of the post opposite that from where the lever 15 is located. The 95 chain is then connected with the hook or projection 8. The reason for this particular manner of connecting the chain with the post is that the forward extremity of the bar equipped as it is with the lever 15, the slide 100 16, and the pawls 10 and 12, is much heavier forward of the post than in the rear thereof, and this weight has a tendency to make the forward extremity of the bar to move downwardly. This it cannot do, since the chain, 105 by virtue of its peculiar location and connection with the post, grips or clamps the post in such a manner as to prevent this downward movement of the forward end of the bar. Hence the bar is held in substantially the horizontal position on the post without special effort on the part of the operator, who is thus free to give his attention to the connection of the wire with the stretcher, for the purpose of beginning the 110 stretching operation. The wire is in the first instance passed into and drawn through the guide 36 at the rear extremity of the bar, after which it is passed between the arms 31 of the guide 30, and after being stretched as 115 far as convenient by hand, the wire is moved into the lowest part of the fork, in which event the barb locks it against rearward movement. Hence the wire is held in the adjusted position until it is clamped by the use 120 of the cam 26. As soon as this is done, the wire stretching operation begins by the manipulation of the lever 15 in the usual manner. It will be understood that by the backward and forward movement of the arm of 130

the lever above the wire, the lever, together with the slide 16 and the pawls 10 and 12, will move forwardly on the bar, drawing the wire with them, by virtue of the clamping action of the cam 26, which is connected with the slide and lever as heretofore explained. After the slide 16 has moved as far as possible on the notched portion of the bar, if the wire is not sufficiently stretched, the cam 29 and the angle member 28 may be thrown to the dotted line position in Fig. 1, and the wire clamped by the use of the last named cam, after which the cam 26 may be released from the wire and the slide and lever moved rearwardly to the point of beginning, after which the cam 29 is released and allowed to assume the full line position in Fig. 1, together with the angle member 28. The wire stretching operation may then be repeated by the manipulation of the lever, in which event the lever and its connections may be again, if desired, moved to the dotted line position in Fig. 1.

Copies of this patent may be obtained for five cents each, by addressing the "Commissioner of Patents, Washington, D. C."

Having thus described my invention, what I claim is:

A barbed wire stretcher comprising a bar equipped approximately midway of its length with a guide for the wire to maintain it in alignment with a plane passed vertically through the bar parallel with its opposite sides during the wire stretching operation, said guide comprising a forked member, and the upper portions of the fork arms being spaced to allow the barbs to pass freely, while the lower extremities of the arms approach each other, to prevent the passage of the barbs when in the lowermost position in the guide, thus serving the additional function of a clamping device.

In testimony whereof I affix my signature, in presence of two witnesses.

CHARLES M. ZARTMAN.
